United States Patent Office

Des. 188,233
Patented June 14, 1960

188,233

TOOTHPICK

Adolph D. Wiseman, 1068 Mission St.,
San Francisco, Calif.

Filed Nov. 24, 1958, Ser. No. 53,496

Term of patent 14 years

(Cl. D85—10)

FIG. 1

FIG. 2

FIG. 3

Fig. 1 is a side elevational view of a toothpick showing my new design, the side opposite thereto being identical in appearance.

Fig. 2 is an end elevational view thereof as seen from the left of Fig. 1; and

Fig. 3 is an end elevational view thereof as seen from the right of Fig. 1.

I claim:

The ornamental design for a toothpick, as shown and described.
